UNITED STATES PATENT OFFICE.

THEODORE N. MATHIAS, OF MILWAUKEE, WISCONSIN, ASSIGNOR TO HIMSELF, LOUIS G. ADAMS AND SAMUEL J. HALL, OF WATERLOO, IOWA, AND DAVID G. WEBSTER, OF CAPRON, ILLINOIS, A COPARTNERSHIP.

LINE SPREADER AND GUIDE.

SPECIFICATION forming part of Letters Patent No. 700,795, dated May 27, 1902.

Application filed September 25, 1901. Serial No. 76,502. (No model.)

To all whom it may concern:

Be it known that I, THEODORE N. MATHIAS, residing at Milwaukee, in the county of Milwaukee and State of Wisconsin, have invented 5 a new and useful Improvement in Line Spreaders and Guides, of which the following is a description, reference being had to the accompanying drawings, which are a part of this specification.

10 My invention has relation to improvements in line spreaders and guides adapted to be employed in various situations upon harness, but more especially adapted for use in connection with the line or the inside check on 15 the line.

The object of the invention is to provide a simple and cheap form of construction capable of acting as an effective guide and as a means for preventing the line or strap from 20 twisting, and, furthermore, of such construction as to provide for the ready removal or insertion of the line or strap and at the same time providing against excessive friction on 25 said line or strap when properly adjusted to the device.

Having the above and other incidental objects in view, the invention consists of the devices and parts or their equivalents, as hereinafter more fully set forth.

30 In the accompanying drawings, Figure 1 is a plan view of my improved device, showing the roller and the strap in section. Fig. 2 is an edge view of Fig. 1, and Fig. 3 is a plan view with the strap removed and the members turned on their pivot in a direction to withdraw the axial studs from the roller.

Referring to the drawings, the numerals 44' indicate two side bars or members. The side bar 4 is provided with an extension 5, projecting at an angle therefrom, and the bar 4' with a similar extension 5', also projecting at an angle therefrom. These extensions are pivoted together, preferably at a medial point and at their outer edges, by a pivot-pin 6. 45 The inner end of each side bar or member is provided with an inwardly-extending stud 7. These studs form the axis for a roller 8, said roller provided with a central opening 9, in which the studs are adapted to pass when the 50 two members of the device are turned on their

pivot in a direction to bring the studs toward each other. The studs loosely fit in the opening 9, so that the roller may freely revolve. Any desirable means may be employed for releasably holding the extensions 55 together; 55 but I prefer to provide each of said extensions with a slot 10. These slots when the members are turned to the position shown in Figs. 1 and 2 are adapted to register with each other, and thereby provide a passage 60 for a strap of the harness—such, for instance, as the spread-strap, (indicated in the drawings by the numeral 11.) The space formed between the roller and the extensions 5 5' receives therein the strap of the harness, preferably 65 the line or the inside check on the line, (indicated in the drawings by the numeral 12.) The width of the space referred to is designed to be such that the strap almost fills up the same, so that said strap will at all 70 times be held flat on the roller and be thereby prevented from twisting. The pull on the line 12 is of course in a direction to bring said line into bearing contact with the roller 8, and hence friction is thereby reduced to 75 the minimum.

It is obvious that the device may be readily removed from the harness when desired merely by pulling out the spread-strap 11 and turning the device to the position shown in 80 Fig. 3. It is equally obvious when the device is in the position shown in Figs. 1 and 2, with the spread-strap passed through the registering slots 10, said strap forms an effective lock against the members being separated 85 or turned on their pivot.

What I claim as my invention is—

1. A spreader or guide for a line or strap, consisting of side bars or members, each provided at a corresponding end with an extension 90 projecting inwardly at an angle therefrom, the said extensions being pivoted together, and each extension being prolonged inwardly beyond the pivotal point, said prolongations adapted to register and overlap 95 each other, when the side bars or members are made to approach each other, a roller located at the opposite ends of the side bars or members, said roller being rotatably engaged 100 with the side bars or members, when said side

- bars or members are made to approach each other, and said roller being disengaged from the side bars or members when the latter are turned on their pivot away from each other, 5 and means constructed to releasably engage the extensions, when the side bars or members are turned in a direction to cause the extensions to approach each other, and the prolongations thereof to overlap.
10. 2. A spreader or guide for a line or strap, consisting of side bars or members each provided at a corresponding end with a slotted extension projecting inwardly at an angle therefrom, the said extensions being pivoted together, and the opposite end of each side bar or member provided with an inwardly-extending stud, a roller provided with an axial opening which the studs are adapted to engage, when the side bars or members are turned in a direction to bring the studs toward each other, and a strap, or other securing means, adapted to be passed through the slots of the extensions when the side bars or members are turned in a direction to cause the extensions to approach each other and the respective slots to register.
15. 3. A spreader or guide for a line or strap, consisting of side bars or members each provided at a corresponding end with a slotted extension projecting inwardly at an angle therefrom, the said extensions being pivoted together, a roller located at the opposite ends of the side bars or members, said roller being rotatably engaged with the side bars or members, when said side bars or members are made to approach each other, and said roller

being disengaged from the side bars or members when the latter are turned on their pivot away from each other, and a strap, or other securing means, adapted to be passed through 40 the slots of the extensions when the side bars or members are turned in a direction to cause the extensions to approach each other and the respective slots to register.

4. A spreader or guide for a line or strap, 45 consisting of side bars or members each provided at a corresponding end with an extension projecting inwardly at an angle therefrom, the said extensions being pivoted together, and each extension being prolonged 50 inwardly beyond the pivotal point, said prolongations adapted to register and overlap each other when the side bars or members are made to approach each other, and the opposite end of each side bar or member provided 55 with an inwardly-extending stud, a roller provided with an axial opening which the studs are adapted to engage when the side bars or members are turned in a direction to bring the studs toward each other, and means constructed to releasably engage the extensions, when the side bars or members are turned in a direction to cause the extensions to approach each other and the prolongations thereof to overlap.

60 In testimony whereof I affix my signature in presence of two witnesses.

THEODORE N. MATHIAS.
